US00D876434S

(12) **United States Design Patent** (10) **Patent No.:** **US D876,434 S**
Lu et al. (45) **Date of Patent:** **** Feb. 25, 2020**

(54) **KEY DEVICE**

(71) Applicant: **Feitian Technologies Co., Ltd.**, Beijing (CN)

(72) Inventors: **Zhou Lu**, Beijing (CN); **Huazhang Yu**, Beijing (CN)

(73) Assignee: **Feitian Technologies Co., Ltd.**, Beijing (CN)

(**) Term: **15 Years**

(21) Appl. No.: **29/662,501**

(22) Filed: **Sep. 6, 2018**

(51) LOC (12) Cl. **14-02**

(52) U.S. Cl.

USPC **D14/383**

(58) **Field of Classification Search**

USPC D14/300–302, 313, 314, 341, 348–370, D14/383, 385, 432, 436, 496, 125, 135, D14/134, 155, 167, 168, 230, 231, 233, D14/235, 237, 240–242, 299; D10/65, D10/75, 78; D13/103, 149, 162, 184, D13/199; D18/4.4–4.6, 12.1, 56; 361/679.31–679.45, 752; 711/100, 115; 382/115, 124

CPC .. G06K 9/00006; G06K 9/6807; G06F 21/32; G06F 17/30

(57) **CLAIM**

The ornamental design for an key device, as shown and described.

DESCRIPTION

FIG. 1 is a perspective view of one embodiment of an key device showing the new design;

FIG. 2 is another perspective view of the embodiment from FIG. 1;

FIG. 3 is a first side elevational view of the embodiment from FIG. 1;

FIG. 4 is a second side elevational view of the embodiment from FIG. 1;

FIG. 5 is a third side elevational view of the embodiment from FIG. 1;

FIG. 6 is a fourth side elevational view of the embodiment from FIG. 1;

FIG. 7 is a top plan view of the embodiment from FIG. 1; and,

FIG. 8 is a bottom plan view of the embodiment from FIG. 1.
